UNITED STATES PATENT OFFICE

2,013,228

RAIL JOINT

Gustaf B. Anderson, Minneapolis, Minn., assignor
of one-half to Oscar T. Nelson, Minneapolis,
Minn.

Application June 27, 1934, Serial No. 732,600

1 Claim. (Cl. 238—219)

This invention relates to joint constructions for railway rails, and the primary object is to provide a novel, efficient, and practical joint design wherein and whereby the adjacent rail ends will be maintained in rigid alignment and with the requisite strength, stiffness, and durability, and yet sufficiently simple and economical of manufacture to be commercially practicable. A further object is to include in such a rail joint provision for longitudinal slippage, due to contraction and expansion of the rails, and to so form the joint design that when contraction of the rails enlarges the space intermediate their ends it will not leave gaps for the car wheels to bridge, but will provide a substantially continuous bearing surface and thereby eliminate the objectionable pounding, wear, and slippage which occurs with the joint constructions now commonly used. Still further and more detailed objects will be disclosed in the course of the following specification, reference being had to the accompanying drawing, wherein:

Fig. 1 is a top or plan view of my improved rail joint showing one of the connected rails secured therein, and the other longitudinally spaced therefrom for purpose of illustration.

Fig. 2 is a side elevation of the structure as shown in plan in Fig. 1.

Fig. 3 is a detail sectional elevation on the line 3—3 in Fig. 1.

Fig. 4 is a perspective elevation of the rail joint block unit as seen separated from the rails which it is to connect.

Fig. 5 is a perspective view showing how the rail ends are formed in order to properly fit the joint block unit.

Fig. 6 is an enlarged, detail section on the line 6—6 in Fig. 2.

Referring to the drawing more particularly and by reference characters, A designates the head or top flange of a conventional type of rail having a vertical web section B, and a base formed by laterally projecting flanges C, supported on the usual cross ties D.

In conventional structures the end surfaces of the rail portions A, B, and C are ordinarily flush with each other. In this instance, however, and to accommodate my improved joint block, the rail head A extends beyond the end limits of the web B, and this extended portion is provided with a V-shaped notch 7, defined by lateral, wedge shaped arms 8.

The joint block comprises several parts all integrally cast or otherwise joined in a single unit. This unit includes a solid central por-

tion 9 continuing, at both ends, in lateral extensions or side walls 10 which are spaced apart, as at 11, to snugly receive the end portions of the rail webs B. The walls 10 and rail webs B are rigidly connected by tie bolts 12, passing through holes 13 therein, and these holes 13 are sufficiently large to permit the necessary rail slippage longitudinally, in slots 11, when the rails expand and contract.

When the rails are in place the wheel supporting flanges or heads A thereof rest upon the upper surfaces 14 of the walls 10, and the arms 8 extend over and bear upon corresponding exposed surfaces of the central block portion 9. Projecting above the surfaces 14 is a central, diamond-shaped lug 15, the opposite ends of which fit snugly into the notches 7; and the upper surface of this lug is flush with the upper surface of the rail head A.

The lower portion of the joint block is formed with laterally projecting flanges 16 which constitute a solid cross base under the central portion 9, but are recessed, as at 17, to receive the base flanges C of the rail. At their outer edges these flanges 16 are notched out, as at 18, to receive spikes 19, and the flanges 16 of course serve to distribute the vibration and rail pressure to the various spikes of each joint.

From the foregoing it will be seen that the rail ends are firmly anchored in place and in alignment with each other. It will also be seen that as the rail head ends have no abrupt transverse shoulders for the car wheels to contact with there will be none of the noise, wear, vibration, or wheel slippage occasioned by such contacts. It will also be seen that notwithstanding the reduction in cross section area of the rail heads, through the arms 8 there is no corresponding objectionable weakening of the rail head structure because of the vertical and transverse bearing support given the arms 8 by the horizontal surfaces 14 and by the vertical surfaces presented by the lug 15. It will further be seen that inasmuch as the lug 15 is integral with the joint block and flush with the rail head it will supplement the arms 8 not only to strengthen the joint, as such, but to greatly relieve the rail head strain adjacent the joint, and by gradually receiving and returning the car wheel stress, intermediate the rail ends, will eliminate the shock and strain which would otherwise occur. It may be stated that strips of leather or other sound and vibration insulating material may be placed between the adjacent vertical surfaces of

the lug 15 and arms 8, but ordinarily this would appear unnecessary.

It is understood that suitable modifications may be made in the structure as disclosed, provided such modifications come within the spirit and scope of the appended claim. Having now therefore fully illustrated and described my invention, what I claim to be new and desire to protect by Letters Patent is:

10 In a rail joint the combination with a pair of aligned rails in each of which the web and base flange ends are cut on a transverse vertical plane and in which the rail head end is notched and projects beyond said plane, of a joint block hav-

ing a solid central portion for resting on a tie between the webs and base flanges of the rails and with an upper lug for engaging the notched rail heads, said block having spaced integrally formed end portions defining recesses for receiving the webs and base flanges of the rails and projecting laterally beyond the base flanges for engagement by spikes to secure the block and rail ends down, the solid central portion of the block being of a width equal to the width of the rail heads so as to bear under and form support for the projecting notched ends thereof, and means for securing the rail webs in said recesses.
